United States Patent Office

Des. 215,613

Patented Oct. 14, 1969

215,613

FINGER RING

Thomas Lawson Wilkinson, Cranston, R.I., assignor to
Walter E. Hayward Co., Inc., Attleboro, Mass., a cor-
poration of Massachusetts

Filed Dec. 10, 1968, Ser. No. 14,863

Term of patent 14 years

Int. Cl. D11—01

U.S. Cl. D45—10

Fig. 1.

Fig. 2.

Fig. 3.

Fig. 4.

Fig. 5.

FIGURE 1 is a perspective view of a finger ring, with the several parts shown in open position, showing my new design;

FIGURE 2 is a right side elevational view with the several parts in closed position;

FIGURE 3 is a left side elevational view, similar to FIGURE 2;

FIGURE 4 is a plan view of FIGURE 2;

FIGURE 5 is an end view of FIGURE 3.

I claim:

The ornamental design for a finger ring, as shown.
